UNITED STATES PATENT OFFICE.

GEORGE D. WANNER, OF DAYTON, OHIO.

KITE OR THE LIKE.

Application filed August 15, 1923. Serial No. 687,629.

To all whom it may concern:

Be it known that I, GEORGE D. WANNER, a citizen of the United States, residing at Dayton, in the county of Montgomery and State of Ohio, have invented certain new and useful Improvements in Kites or the like, of which the following is a specification, reference being had therein to the accompanying drawings.

10 This invention relates to improvements in kites.

The objects attained in the improvements herein illustrated and described are as follows:

15 A kite which is better adapted to be manufactured by automatic, or semi-automatic machinery, whereby cheaper production will be effected.

A kite which will be better made and 20 therefore more durable than kites of common construction.

A kite which will have distinctive artistic effect without added cost of production.

In the drawings these features are illustrated in three common types of kites, viz, 25 two-stick kite, three-stick kite, and square or Chinese kite,—the main principles of the invention applying equally to the different types.

30 Figs. 1, 2 and 3, are front elevations illustrating respectively the three types of kites herein referred to and the improvements of the present invention.

Fig. 4 is a sectional view taken on line 35 4—4 of Fig. 1.

Fig. 5, is a transverse sectional view taken on line 5—5 of Fig. 2.

Fig. 6, is an enlarged view illustrating a detail of construction.

40 Fig. 7, is a sectional view taken on line 7—7 of Fig. 6.

Fig. 8, is a sectional view taken on line 8—8 of Fig. 6.

Fig. 9, is a detail view of Fig. 2.

45 Fig. 10, is a detail showing the manner of setting the staples in the kite sticks.

Fig. 11, is a detail of the end of a kite stick, and

50 Fig. 12, is a detail of a reinforcement applied to the kite cover.

The general construction of the three types of kites illustrated in the drawings is well known in this art. The frame of the kite illustrated in Fig. 1 consists of a main stick or strut —1 and a cross or bow stick —2 to which the kite cover —3 is at-

tached. The kite shown in Fig. 2, has two main sticks —4, a cross stick —5 and the kite cover —6, and the kite shown in Fig. 3, has a main stick —7, a bow stick —8, and 60 the kite cover —9. No novelty is claimed in the present invention with respect to these main features of the several types of kites here shown, the assembly and general arrangement of the parts being such that the 65 kites can readily be folded and rolled in knock-down form.

A main feature of the invention consists in a bounding tape —10 applied to the edge surrounding the kite cover, the manner of 70 applying the tape being the same for each type of kite shown. The bounding tape, made of any suitable material, as light weight paper having relatively high tensile strength, can be applied to the kite cover in 75 any suitable manner, preferably by using an adhesive, as paste or glue, in either single or multiple thickness as may be desired to give strength to the border of the kite cover. As shown in the drawings best illus- 80 trated in detail Fig. 7, the tape is folded once to overlap the edge of the cover on both sides and is glued to the cover material.

The bounding tape —10 can be applied 85 to the kite cover in any suitable lengths,— in a single strip extending entirely around the cover, or a number of strips extending preferably from one corner to another of the kite cover. In the drawings the latter 90 arrangement is shown, the adjoining ends of the strips overlapping one another where the junctures are made as shown at —11, in Fig. 8, thus providing for quadruple 95 strength of the tape material at the corners for attaching the kite cover to the frame.

The bounding tape as shown and described has the following distinctive advantages: it eliminates the bounding cord which is commonly used on kites of the character 100 shown; it is a better protection for the edge of the kite cover than a bounding cord; it adapts the kite cover, including application thereto of the bounding tape, to be made by special automatic machinery and lowers production costs accordingly; and it lends itself readily without added cost to give artistic effect to the kite, as striking color combinations of the kite cover and the bounding tape is merely a matter of selection. 110

The bounding tape also adapts the kite cover to be attached to the frame by a novel

arrangement consisting in forming a hole, or eyelet —12 through the reinforced corners —11 of the kite cover, which adapts the cover to be attached to the kite frame by 5 means of tenons —13 formed on the ends of the frame sticks which are adapted to project through the eyelets —12 to form the connection.

It will be obvious from the arrangement 10 here shown that the eyelets —12 can be used as a means for attaching the kite cover to the frame irrespective of the tape —10 by reinforcing the corners of the kite cover in any suitable manner to support the eyelets, 15 also that the eyelets can be connected to the kite sticks by other means than the tenons —13; also that the kite cover can be attached to the tenons —13 by other means than the eyelets —12. As far as the applicant is 20 aware both these features—eyelets —12 and tenons —13—are novel in the known practice of kite making, and various modifications of the arrangement here shown can readily be made without departing from the 25 principle of the invention.

A detail of improvement is also shown in the several figures of the drawings, consisting of reinforcements —14 applied to the kite cover and slotted as at —15, to receive 30 the staples —16 to which the bridle string —17 is attached, the flying string —18 being connected to the bridle string, the reinforcements serving to prevent tearing of the kite cover around the edges of slots 15.

35 A further detail improvement is shown in Fig. 2, consisting of a novel arrangement of the bridle string for three-stick kites. The usual arrangement consists of three bridle strings extending over the kite cover parallel with the kite sticks, the flying string being connected to the bridle strings at the 40 point of their intersection. The arrange-

ment here shown is much simpler consisting of but one bridle string —16, having its ends tied to opposite staples —18 secured in 45 the cross stick —5.

Having described my invention, I claim:

1. A kite including in combination with the cover thereof, a bounding tape consisting of strips folded to overlap the edge of 50 the cover and having adjoining ends thereof overlapping one another at the corners of said cover.

2. A kite including in combination with the cover thereof, a bounding tape applied to reinforce the edge and corners of said cover, and an eyelet formed in each of said corners to attach said cover to the kite sticks. 55

3. A kite including in combination with 60 the cover thereof, reinforcements applied to the corners of said cover and eyelets formed in said reinforced portions whereby to attach the cover to the kite sticks.

4. A kite including in combination with 65 the cover thereof, kite sticks having tenons formed on the ends thereof, and eyelets formed in the kite cover whereby to attach said cover to the kite sticks.

5. A kite including in combination with 70 the cover thereof, kite sticks having tenons formed on the ends thereof, and means for attaching the kite cover directly to said tenons.

6. A kite comprising two main sticks and 75 a cross stick, a kite cover having apertures formed therein spaced one from another longitudinally relative to said cross stick, staples secured in the cross stick and projecting through said apertures and a bridle string tied to said staples. 80

In testimony whereof, I affix my signature.

GEORGE D. WANNER.
